UNITED STATES PATENT OFFICE.

DANIEL FOCER, OF CAPE MAY, NEW JERSEY, ASSIGNOR OF ONE-HALF TO
THOMAS G. LOVEGROVE, OF PHILADELPHIA, PENNSYLVANIA.

BOILER-ALARM.

SPECIFICATION forming part of Letters Patent No. 431,885, dated July 8, 1890.

Application filed September 6, 1889. Serial No. 323,130. (No model.)

To all whom it may concern:

Be it known that I, DANIEL FOCER, a citizen of the United States, residing in the city and county of Cape May, State of New Jersey, have invented a new and useful Improvement 5 in Electrical Water-Alarms, which improvement is fully set forth in the following specification and accompanying drawings.

My invention relates to electrical water- 10 alarms for use with water columns and gages for steam-boilers, tanks, cisterns, reservoirs, &c.

The invention consists of a mechanical apparatus, as herein described, in connection 15 with electrical devices relatively coacting to indicate the position of a volume of water by sounding an alarm.

Figure 1 represents a side elevation of a water-gage, showing my invention applied 20 thereto. Fig. 2 represents a horizontal section of the water-gage, showing a part of my improvement in connection therewith. Fig. 3 represents a view similar to Fig. 1, showing 25 a modification of the invention. Fig. 4 represents a view similar to Fig. 2, showing the modification applied thereto. Fig. 5 represents a detail view in rear elevation of the 30 form of index used in the construction shown by Figs. 3 and 4.

Similar letters and numerals of reference 35 indicate corresponding parts in the several figures.

Referring to the drawings, A designates the 40 body or shell of a water column or gage adapted to be suitably connected to a steam-boiler, tank, &c., said device being illustrated for convenience in showing the application of my improvement, it being understood that the invention may be applied to other devices. 45 A float B is mounted in said body A, and is attached to a rock-shaft C, having a projecting end for connection therewith of an index D, said mechanism being adapted to indicate the level of the water in the boiler by rising and falling, as will be readily understood.

On the shell or casing A are affixed contact 50 points or posts 1 and 2, and to the index D, Figs. 1 and 2, is connected a metallic contact 3, separated from said index by an interposed insulation 4. The shell or casing A is also provided with a binding-post 5, to which is attached a wire 6, running to one pole of a

battery 7, and thereby including the said shell or casing A in the electric circuit. The contact 3 has a wire 8 connected thereto and to one post of a bell or signal E, the other post of said bell or signal being connected by a wire 10 to the opposite pole of the battery 7. 55

The float B lowers when the water in the gage attains a low level, and the index D falls therewith, bringing the contact 3 over the post or point 2, and the circuit is completed through wire 10 to bell E to ring the same, from bell E to battery 7 by wire 10, and from battery 7 back to shell or casing A through wire 6. In the event of high water, contact 3 60 engages post or point 1, and the circuit is completed as before. The alarm will be electrically sounded by bell E in both instances, and attention thereby called to the condition 65 of the water in the boiler, tank, &c.

As shown by Figs. 3, 4, and 5, the apparatus is modified by the addition of another circuit, including an annunciator. The contact 3 in this instance is formed in two sections, 70 having wings 15 and 16, separated by insulating material, as shown in Fig. 5, and unitedly insulated from said index, as at 4. (See Figs. 1 and 2.) The upper section of said contact is adapted to engage post 1 on shell A, and 75 has a wire 8 connected thereto and running to a post 13 on an annunciator F and actuating the high-water index, the circuit being completed through battery-post 12 of said annunciator, which has a wire 11 attached thereto and running to one of the posts of bell E to ring the same, by wire 10 from the other post of said bell to one pole of battery 7, and from the opposite pole of said battery by wire 6 back to the shell or casing A. When the 80 lower wing 16 of contact 3 engages a post 2, the circuit is made through a wire 9, connected with the lower section of said contact, running to the binding-post 14 of annunciator F, to actuate the low-water index, out through battery-post 12 by wire 11 to bell E to ring the same, from bell E by wire 10 to one pole of battery 7, and from the opposite pole of battery 7 back to the shell or casing A. By this 85 means an alarm is sounded on bell E in the event of high or low water, and the annunciator F, located in a desirable place, designates whether the water be high or low in the boiler, reservoir, &c. The posts or points 1

and 2 will be located in such position as to be in advance of the danger-point of too high or too low water line.

Having thus described my invention, what I claim as new, and desire to secure by Letters Patent, is—

A device for the purpose named, consisting of an electric circuit with a battery and an alarm, a receptacle with contact-points, a rock-shaft carrying a float within said receptacle and an index outside of the same, said index

being between said contact-points, and a metallic contact connected with one pole of the battery and carried by the index, but insulated therefrom, the wire connected with the other pole of the battery being secured to a binding-post on said receptacle separate from the contacts, substantially as described.

DANIEL FOCER.
